UNITED STATES PATENT OFFICE

EDWIN C. JACKSON, OF ST. LOUIS, MISSOURI, ASSIGNOR, BY MESNE ASSIGNMENTS, TO
GENERAL STEEL CASTINGS CORPORATION, OF GRANITE CITY, ILLINOIS, A CORPORA-
TION OF DELAWARE

LOCOMOTIVE STRUCTURE

Application filed June 6, 1929. Serial No. 369,272.

My invention relates to railroad locomotives and particularly to the brake cylinders and associated structure and consists in a novel saddle member which can be used in connection with the main steam cylinders, steam supply chambers, boiler support and adjacent framing or bed structure of a locomotive.

The main objects of my invention are to reduce machining and assembling of the brake cylinder structure and the saddle member on which they are mounted; to avoid the necessity of frequent inspection and tightening of brake cylinder mounting elements; to simplify the construction of the parts mentioned; and to render the same more rigid and less likely to require repairs.

Another object is to form a fluid passage-way integral with the brake cylinder body and saddle structure.

I have developed my invention with special attention to the equipment utilizing compressed air as the operating medium but I contemplate the use of vacuum, steam, oil or other forms of pneumatic or hydraulic brake systems.

I attain these objects by forming one or more brake cylinder elements integrally with the locomotive saddle structure which forms a transverse brace for the locomotive under-frame and this structure can also carry the steam cylinders and the smoke-box or adjacent portion of the boiler shell. Preferably, the saddle, boiler support, main steam cylinders, steam supply chambers and brake cylinder elements will all be formed integrally with each other and with the locomotive framing or bed structure, although the complete integral formation referred to is not essential to the broadest form of my invention.

Preferably the integral structure includes the cylinder body and one cylinder head but the body only or a head only may be the only cylinder element integral with the saddle structure.

In the accompanying drawings which illustrate my invention—

Figure 1 is a top view of a cylinder and boiler support saddle with integral brake

cylinder bodies, a portion of the structure being sectioned to more clearly illustrate the same.

Figure 2 is a rear elevation of the same.

Figure 3 is, in part, a side elevation and, in part, a vertical longitudinal section taken on the line 3—3 of Figure 2 and indicating the connection of the brake cylinder to the brake lever.

Figure 4 is a top view, sectioned in part to more clearly illustrate the same, of the preferred form of my invention and comprises a locomotive saddle and brake cylinder structure integral with the locomotive bed.

Figure 5 is a side elevation of the structure shown in Figure 4.

Figure 6 is a vertical transverse section taken on the line 6—6 of Figure 4. In this construction, the saddle, steam and air cylinder bodies, etc. are formed integrally with the locomotive bed.

Figure 7 is a front view of a modified structure in which the saddle, steam cylinders and locomotive framing are separate from each other.

Figures 8, 9 and 10 are similar to Figures 4, 5 and 6 but illustrate a modified structure particularly adapted for use over a two wheel truck, Figure 10 being a section taken approximately on the line 10—10 of Figure 8.

Figure 11 illustrates another modification of my invention described in detail below.

Figures 12 and 13 are, respectively, a front view of and longitudinal vertical section through another modified form of my invention.

Figures 14 and 15 are, respectively, a front view and half plan view of another modified form of my invention, a portion of the plan view being sectioned to more clearly illustrate the same.

In the structure illustrated in Figures 1, 2 and 3, the saddle is shown as extending across the locomotive side frames 1 and comprising a body portion having front and back walls 2, a bottom wall 3, a top wall 4 having an extension 5 forming a boiler support. The main steam cylinders 6, with individual steam supply chambers 7 and inlet passageways 8, are formed integrally with the saddle

75

80

85

and the rear vertical wall 2 of the saddle is a part of brake cylinder bodies 9 formed integrally therewith and projecting from the wall with their axes disposed horizontally 5 and the wall 2 of the saddle forming the inner ends or heads of the cylinder bodies 9. The outer ends or heads 10 of the cylinder bodies are formed separately and secured to the cylinder body side walls by studs, bolts or welding.

10 The saddle wall 2 is recessed as indicated at 11 to provide an air passage from a supply pipe 12 at the side of the cylinder body 9 to the interior of the body and the wall is similarly recessed at 13 to provide an air passage between the adjacent brake cylinder bodies 9.

15 A bushing 59 is preferably inserted in the cylinder so as to provide renewable means for wear on the interior of cylinder walls.

20 A saddle of this type may be readily cast in one piece and machined in the usual boring machines and applied to the ordinary locomotive frames without special work on the latter.

25 In the construction shown in Figures 4, 5 and 6, the locomotive framing comprises a box-shaped section having a bottom wall 14, side walls 15 and a top wall 16, and a saddle member extending transversely of the box-shaped section 14-15-16 and above the same and including a front wall 17 and a rear wall 18. Steam cylinders 19 and supply chambers 20 are integral with the framing and saddle structure and the latter also includes an integral boiler support 21. Projecting rearwardly from the rear wall 18 of the saddle structure are the curved walls 22 which merge with each other to form a common partition wall or web 22^a and also merge with the wall 18 and cooperate to form horizontally disposed brake cylinder bodies 23 having removable bushings 60 and removable non-pressure ends 24 provided with release spring recesses 25. A projection F, integral with the bottom wall 14 of the bed, provides a fulcrum for the mounting of the brake lever indicated at L. Obviously, the relation between the same and brake cylinder body 23 will be maintained throughout the life of the locomotive structure.

30 In this preferred construction, the parts specifically referred to are integral with the entire locomotive bed which includes the front deck 26, the pilot beam 27, the valve gear support brackets 28, pedestals 29, etc. I prefer to form these parts by casting the same in one piece but it is practical to make some of the parts separate from each other by casting or by any combination of the methods of casting, welding, forging, etc., and then unite them by welding. In any integral structure, whether formed by casting or welding or otherwise, the elimination of attaching flanges, bolts or rivets, and the necessity of

35 providing space for getting at the attaching elements for original installation or for maintenance or repairs, and the elimination of fitting of the parts for original installation and the elimination of play between the parts, due to wear and use, are some of the marked 70 advantages which are not present in the built-up structures previously used.

40 In the modification illustrated in Figure 7, I show a saddle 30 having a single air brake cylinder 31 formed integrally therewith with its axis disposed vertically and with both ends of the cylinder 32 and 33, respectively, detachably mounted on the cylinder, the side wall of the cylinder being braced, by suitable 75 ribs 34, at points spaced from the upright wall of the saddle. This structure illustrates a saddle applicable to the frames 35 of the locomotive and also shows the steam cylinders 36 and supply chambers 37 formed separately 80 and applied to the saddle in accordance with a well-known practice.

45 In Figures 8, 9 and 10, I show a pair of air brake cylinders 38 disposed vertically and mounted at points spaced from the saddle wall 39 by means of brackets 40 provided with recesses 41 for lightening the same and facilitating the casting of the cylinders integrally with the saddle structure. The saddle is formed integrally with the longitudinal members 42 of the bed and includes integral steam cylinders 43, supply chambers 44 and a boiler support 45. Exhaust passages 46 extend inwardly of the saddle outer walls and unite in a centrally disposed exhaust nozzle 47, similarly to the corresponding parts in the structure shown in Figure 4. Both ends 48 of cylinders 38 are removable, which may be desirable under some manufacturing conditions or for other reasons.

50 In Figure 11, I illustrate a detail of a very similar construction in which the non-pressure head 49 of the cylinder 50 is formed integrally with the same and with the bracket 51 which unites the cylinder with the saddle 52, but the pressure head 53 is removably applied to the cylinder 50 in the usual manner.

55 In Figures 12 and 13, I illustrate a modification particularly adapted for a three cylinder locomotive in which the space immediately under the boiler support 54 is not available for mounting the brake cylinder due to the projecting parts on or associated with the steam cylinder 55. In this structure, I provide a brake cylinder 56 beneath the steam cylinder 55 and disposed on an incline similar to cylinder 55, the inner end 57 of the brake cylinder forming an intermediate wall or rib for the saddle 58 and serving to brace the same and the lower wall of the steam cylinder 55.

60 In Figures 14 and 15, I illustrate another modification of the saddle structure in which

the complete saddle is formed in two halves 61 and 62, each of which includes a main steam cylinder 63, a steam supply chamber 64, a boiler support flange 65 and a brake cylinder body 66. The saddle members are provided with flanges 67 for attachment to each other and with suitable elements 68 for attachment to the brace 69 of the locomotive frame. Each of the saddle members 61 and 10 62 has a wall 70 which forms the inner or pressure head of the cylinder and the side wall 71 of the cylinder is integral with and projects from the saddle wall 70. Clearly, this type of saddle member could have a vertically disposed cylinder integral therewith in place of the horizontally disposed cylinder illustrated.

In each of the Figures 3, 5 and 9, I illustrate the adjacent truck wheels, brake lever, 20 piston, release spring and connection rods, but it will be understood that these elements do not form any part of my present invention as they have long been in common use and I illustrate them merely to show their position 25 relative to the brake cylinders with which they are associated.

Various other modifications of the details of the device and relative arrangement of the parts shown may be made without departing 30 from the spirit of my invention and I contemplate the exclusive use of such variations as come within the scope of my claims.

I claim:

1. A locomotive saddle member having a 35 brake cylinder element integral therewith.
2. A locomotive saddle member having a brake cylinder head integral therewith.
3. A locomotive saddle member having an upright wall, and a brake cylinder head 40 formed integrally with said wall and projecting therefrom.
4. A locomotive saddle member wall forming the head of a brake cylinder.
5. A locomotive saddle member having 45 a portion of said saddle forming a wall of said cylinder structure.
6. A locomotive saddle member having an upright wall, and a brake cylinder body 50 formed integrally with said wall and projecting therefrom.
7. A locomotive saddle member having an upright wall, and a brake cylinder body 55 formed integrally with said wall and projecting therefrom with its axis disposed substantially horizontally and with said wall forming the inner end of said cylinder body.
8. A locomotive saddle member having an upright wall, and a brake cylinder body 60 formed integrally with said wall and projecting therefrom, there being an air passage-way formed in said wall and leading from outside of said member to the interior of said cylinder body.
9. A locomotive saddle member having a 65

main steam cylinder, and an air brake cylinder body formed integrally therewith.

10. A locomotive saddle member having a main steam cylinder, a steam supply chamber, and a brake cylinder body, all formed integrally.

11. A locomotive saddle member having a boiler support element and a brake cylinder body formed integrally.

12. In an integral structure for a locomotive, a longitudinal frame member, a transverse saddle member, a brake cylinder body on said saddle member, and a brake lever fulcrum on said frame member, whereby a predetermined relationship between said fulcrum and said cylinder is maintained throughout the use of the structure.

13. In a locomotive, a longitudinal frame member, a transverse saddle member, a brake cylinder on said saddle member, and a brake lever fulcrum on said frame member all of said parts being integral with each other whereby a predetermined relationship between said fulcrum and said cylinder is maintained throughout the use of the structure, and a renewable bushing in said cylinder.

14. In an integral structure for a locomotive, a saddle member, a main steam cylinder, a boiler support element, and a brake cylinder body, all formed integrally.

15. A locomotive saddle member having a main steam cylinder and a brake cylinder body all formed integrally therewith, the axes of said steam cylinder and said brake cylinder body being parallel with each other.

16. In combination, a locomotive saddle structure, main steam cylinders on opposite sides of said structure, and one or more brake cylinder bodies located between said steam cylinders, all of said parts being formed integrally with each other.

17. In combination, a locomotive saddle structure, main steam cylinders on opposite sides of said structure, individual steam supply chambers for said cylinders, and one or more brake cylinder bodies located between said steam cylinders, all of said parts being formed integrally with each other.

18. A locomotive saddle structure having a pair of brake cylinder bodies formed integrally therewith and including a common wall between them.

19. In a locomotive saddle structure, an upright wall, a web integral with and projecting from said wall, and a pair of brake cylinder bodies integral with the saddle structure, each having an end formed by said saddle wall and each having a side wall formed in part by said web.

20. In a locomotive bed, a frame portion extending longitudinally of the locomotive and having a box-shaped cross section, a saddle extending transversely of said frame portion and including an upright wall and a boiler support member, and a brake cylinder

body mounted on said wall, all of said parts being integral with each other.

21. In a locomotive bed, a frame portion extending longitudinally of the locomotive and having a box-shaped cross section, a saddle extending transversely of said frame portion and having a box-shaped cross section, and a brake cylinder body projecting from said saddle portion, all of said parts being integral with each other and a wall of said saddle portion forming a part of the wall of said body.

22. A locomotive saddle member having an upright wall, and a brake cylinder body formed integrally with said wall and projecting therefrom, there being an air passage-way formed in said wall and leading to the interior of said cylinder.

In testimony whereof I hereunto affix my signature this 13th day of May, 1929.

EDWIN C. JACKSON.
